UNITED STATES PATENT OFFICE.

CHARLES V. CRAIG, OF LOS ANGELES, CALIFORNIA.

FLUME CONSTRUCTION.

1,078,835.

Specification of Letters Patent.

Patented Nov. 18, 1913.

Application filed February 8, 1913. Serial No. 747,088.

To all whom it may concern:

Be it known that I, CHARLES V. CRAIG, a citizen of the United States, and residing in the city of Los Angeles, county of 5 Los Angeles, State of California, have invented a new and useful Improvement in Flume Constructions, of which the following is a specification.

This invention relates to flume constructions and particularly to providing a flume of reinforced concrete, and the principal object of the invention is to provide a construction which will utilize discarded cables which have become somewhat worn and are 15 no longer considered suitable for conveying work.

It is also an object to provide such a flume construction with adjustable brackets by which the cables may be suitably supported 20 in relation to the surface over which it is desired to carry the flume.

It is a further object to provide a concrete flume construction with a reinforcement in the form of wire netting or expanded metal which can be readily secured, by 25 means of suitable lashings, to the supporting cables.

In the drawings, Figure 1 is a view of a flume showing the supports used to carry 30 the same over uneven surface of the ground. Fig. 2 is an enlarged detail cross-section of the flume and one set of its supports. Fig. 3 is a longitudinal detail of a portion of the upper edge of the reinforcement and 35 the cable, a portion of the cement structure being included. Fig. 4 is an enlarged detail showing the cross-section of the cable and a small portion of the reinforcement and the lashing therefor.

40 More specifically in the drawings, the numeral 5 designates the surface of the ground over which the flume 6 is supported by means of the vertical uprights 7, placed at suitable intervals and braced by means of 45 the diagonal timbers 8. The uprights 7 are preferably provided with a vertical bore 9 forming a socket within which the supporting rods 10 are adjustably mounted, this adjustment consisting of the threaded shank 50 11 of the metal support, provided with the adjusting nut 12 which engages with the washer 14 resting on the top of the timber supports.

The upper ends of the rods 10 are preferably bent at right angles to the shank 11 and extended to provide an ear 15, through

which a bore is carried of sufficient size to engage the cable 16.

The cables commonly used for the purposes mentioned are formed of wire of a 60 number of strands, and the rods 10 are strung on one end and carried along to the supports, which are placed at the required interval to form the size flume desired.

To form a reinforcement for the flume, 65 which, as shown, is preferably semi-circular in cross-section, a strip of expanded lath or wire netting 17 is used extending from the lower portion of one cable, in the proper configuration, to the opposite and parallel 70 cable 16, the netting 17 being secured by suitable lashings, preferably of metal, shown as rings 18 mounted on the cables 17 and engaging with the edge of the strand of the netting. 75

By use of suitable forms, or by simply troweling a sufficient quantity of cementitious material 19 in engagement with the netting, the flume is formed, this material being preferably carried up over the cable, 80 as shown, at the point 20, so that all the metal parts are covered by the cementitious material and the bars 10 are included from the point 21 inwardly. By this means, 85 flumes can be quickly and economically constructed in sections where suitable materials to form a support therefor are difficult to obtain and expensive in character, as well as utilizing cables which have become practically worthless and are not of 90 sufficient value to ship where they can be worked over.

What I claim is:

1. A flume construction, comprising a flume, a flexible suspension means connected to said flume, and supports for said suspension means. 95

2. A flume construction, comprising a flume having sides, a flexible suspension means connected to said sides, and means to 100 adjustably support said flexible suspension means.

3. A flume construction, comprising a flume formed of concrete, a flexible cable supporting said flume, adjustable connections secured to said cable, and means to support said adjustable connections. 105

4. A flume construction, comprising a metallic webbing, a plurality of flexible cables connected to said webbing, supporting connections secured to said cables, supports for said supporting connections, and 110

a cementitious material secured to said webbing and inclosing the same.

5. A flume construction, comprising a metallic netting, a pair of flexible cables, means to connect said netting to said cables, supporting rods secured to said cables, supports for said supporting rods, and a cementitious material secured to said netting and cables and inclosing the same.
- 10 6. A flume construction, comprising a continuous trough-like structure, a pair of

suspension cables connected thereto and adapted to support said trough-like structure above the surface of the ground, and supports for said cables.

15 In witness that I claim the foregoing I have hereunto subscribed my name this 28th day of January, 1913.

CHARLES V. CRAIG.
